UNITED STATES PATENT OFFICE.

WILL RICE SALTZGABER AND CAWOOD JOHNSON CARMICHAEL, OF
KNOXVILLE, TENNESSEE.

SOAP-DISPENSING APPARATUS.

SPECIFICATION forming part of Letters Patent No. 787,700, dated April 18, 1905.

Application filed May 27, 1904. Serial No. 210,072.

To all whom it may concern:

Be it known that we, WILL RICE SALTZGABER and CAWOOD JOHNSON CARMICHAEL, citizens of the United States, and residents of 5 Knoxville, in the county of Knox and State of Tennessee, have invented a new and Improved Soap-Dispensing Apparatus, of which the following is a full, clear, and exact description.

10 Our invention relates to apparatus for the dispensing of soap, having for its principal objects the provision of a simple, convenient, and economical apparatus to which the soap may be supplied and maintained in use in an 15 absolutely sterile condition and without evaporation.

With these ends in view the invention consists in the various features hereinafter described and more particularly claimed.

20 Reference is to be had to the accompanying drawings, forming a part of this specification, in which similar characters of reference indicate corresponding parts in all the figures.

Figure 1 shows in perspective a lavatory 25 in connection with which one embodiment of our invention is illustrated. Fig. 2 is a central vertical section therethrough, taken in the plane of the supporting-bracket. Fig. 3 is a transverse section on the line 3 3 of Fig. 2, and Fig. 4 is a detail in elevation of the operating-arm.

10 designates a receptacle for containing soap, it being here shown as consisting of a glass bottle or vessel having a contracted neck 35 11. This is normally held in an inverted position upon a casing 12 by means of a connecting and supporting collar 13, provided with an internal thread at 14 for engaging a thread formed upon the bottle-neck. Between the 40 end of said neck and a shoulder 14^a in the sleeve may be interposed a packing-ring 14^b for the purpose of forming a fluid-tight joint. Outside the thread 14 is a flaring portion 15, which may conform to and support the wall 45 of the bottle adjacent to the neck. Beyond the shoulder 14^a the collar has a somewhat reduced portion 16 externally threaded to engage a thread formed upon the interior of a neck or conduit 17 projecting from the

casing. The casing is provided at a point 50 preferably ninety degrees from the neck 17 with a stem 18 for engagement with a support or bracket 19, to which it may be conveniently connected by a union 20. The bracket may have at its opposite extremity a plate or flange 55 21 for attaching it to the lavatory or the wall upon which it is to be supported. Opposite the supply-conduit of the casing is a delivery-conduit 22, at the end of which is a reduced portion 23. Surrounding this delivery-conduit is a contracted delivery-nozzle 24, conveniently formed of sheet metal or vulcanized rubber and having a projection 25, which may engage a depression in the wall of the conduit. This nozzle is shown as provided with 65 a plurality of comparatively small openings 26, situated opposite the portion 23 of the conduit.

Within a suitable recess or bore in the casing operates a valve body or plug 27, which is preferably tapered and is secured in place by a screw 28 with an intermediate washer 29 in the usual manner. This plug is provided with a plurality of pockets or recesses P, these in the present instance being shown as four in 70 number and equally spaced from one another about the circumference of the plug. At the opposite side of the plug from its securing-screw is a stem 30, in which are bores 31 31, lying in different vertical planes and at right 75 angles to one another. In these bores operate sliding dogs 32. Surrounding the stem is a hub 33 of an operating member or arm 34, the interior of the hub being provided with a ratchet-tooth or projection 35, preferably extending the full width of the hub, for engagement with the dogs. The arm may be secured in place upon the stem by a plate 36, held in position by screws 37. To the outer end of the arm is pivoted a link, which is here shown as 80 formed in two sections, the upper one, 38, consisting of a rod which enters a tubular member 39 and is adjustably secured thereto by a setscrew 40. The lower section 39 is articulated to a treadle 41, which may be pivotally 85 mounted upon a bracket 42, fixed to the floor, and which is provided at its outer end with a pad 43. The treadle may be normally held 90

in its raised position by a spring 44, connected to it and the floor and here shown as of the tension type.

In the use of our improved dispensing apparatus in connection with a lavatory, such as is illustrated at L in Fig. 1 of the drawings, the securing-plate of the bracket may be attached to the back slab by screws 45, the nozzle being preferably located in the plane 10 and at about the same height as the outlets of the bibbs. The connecting-rod may pass through a hole formed through the basin-slab and the treadle-bracket be fixed to the floor in such a manner that when the pad is 15 raised the operating-arm will occupy its lowest position, as is shown in full lines in Fig. 2. Opposite pockets in the plug will then be situated in alinement with the passages of the supply-conduit and delivery-conduits and the 20 projection of the ratchet mechanism will be in contact with one of the dogs. The soap, preferably in a liquid form, may be supplied in the bottle 10 suitably stopped. To apply a bottle to the apparatus, the union is disconnected and the 25 casing then turned about the body of the valve until the supply-conduit is at the under side. The bottle may then be screwed tightly upon the connecting-collar, whereupon the casing is inverted and secured in place upon the bracket 30 by the union. The detergent liquid then descends by gravity into the pocket alined with the passage through the neck of the bottle, displacing the air therein, the amount contained in the pocket being suitable for a single cleansing operation—say thirty minims. Now when it is desired to secure a charge of the soap it is only necessary for the user to depress the treadle with the foot, bringing the operating-arm to the position indicated in 35 40 dotted lines in Fig. 2 and resulting in the rotation of the plug through a quarter of the circumference, thus bringing the pocket which has been previously filled into alinement with the delivery-conduit, when the contents of the 45 pocket will descend into the discharge-nozzle, and the air entering above it through the openings 26 will allow it to flow through the

nozzle-opening into the hands of the user placed to receive it. This brings the second dog into coaction with the ratchet projection, 50 permitting it to act upon the next depression of the treadle and bring the succeeding pockets opposite the supply and delivery conduits.

Our improved apparatus is particularly adapted for all public places where the toilet 55 articles are promiscuously used, since it not only effects economy, but will absolutely obviate the danger of infection from the use of soap which has been contaminated by persons previously handling it. In this connection it 60 should be noted that not only can the soap be supplied to the receptacle in a sterile condition and so maintained, but that it is also unnecessary for the user to handle any portion of the apparatus. 65

Having thus described our invention, we claim as new and desire to secure by Letters Patent—

1. A soap-dispensing apparatus comprising a valve-casing, a receptacle separably connected therewith, a bracket, a union connecting the bracket and casing, a valve rotatable within the casing, and a treadle connected with the valve. 70

2. A soap-dispensing apparatus comprising a receptacle, a valve for controlling the discharge therefrom, an operating-arm for the valve, a treadle, a link connecting the arm and treadle, and means for varying the length of the link. 75 80

3. A soap-dispensing apparatus comprising a receptacle, a delivery-conduit leading therefrom and having its end of reduced diameter, and a nozzle surrounding the end of the conduit and being provided with an opening opposite the reduced portion thereof. 85

In testimony whereof we have signed our names to this specification in the presence of two subscribing witnesses.

WILL RICE SALTZGABER.

CAWOOD JOHNSON CARMICHAEL.
